GRINDING MACHINE

Frederick S. Haas, Cincinnati, Ohio, assignor to
Cincinnati Grinders Incorporated, Cincinnati,
Ohio, a corporation of Ohio

Application October 27, 1937. Serial No. 171,310

13 Claims. (Cl. 51—103)

2000-0004-0001-0001

This invention relates to improvements in grinding machinery of the centerless type and has particular reference to the type of machine illustrated in United States Letters Patent No. 1,872,405.

One of the principal objects of the present invention is the provision in connection with a machine of the type there illustrated of a novel and improved feeding mechanism for presentation of work pieces to the grinding throat.

A further object of the present invention is the provision of an improved automatic machine of the magazine type for continuous operation in controlled grinding of successive work pieces.

11. A further object of the present invention is the provision of a feed mechanism embodying improved safety features for automatically stopping the machine upon any interference with the proper flow of work through the grinding throat.

20 Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

30 Figure 1 is in part a transverse section and in part an elevational view of the work control mechanism at the grinding throat of the machine.

Figure 2 is a vertical sectional view taken on the line 2-2 of Figure 1.
Figure 3 is a sectional view through the synchronized driving mechanism for controlling the operation of the parts in question.

operation of the parts in proper timed sequence. Figure 4 is a fragmentary rear view illustrating the end stop and ejecting mechanism, and Figure 5 is a simplified diagram of the essential electrical controls for the machine.

In the drawings in which similar characters of reference are employed to denote corresponding parts throughout the several views, numeral 10 designates the bed of a grinding machine of conventional centerless type having rotatably mounted thereon at one end thereof a pair of spaced grinding wheels 11 for operation on the terminal portions of an armature shaft or other work piece 12. Disposed in opposition to these grinding wheels is a regulating wheel support 13 mounted for oscillation about a suitable trunnion 14. Oscillation of the support serves, as in the Patent 1,872,405 previously referred to, to

move the regulating wheel 15 in a direction toward and from the grinding wheels 11, pressing an interposed work piece 12 thereagainst, the work piece riding on the customary work support blade 16 during this operation.

To effect this movement of the regulating wheel unit, the member 13 is provided with an abutment 17 riding on cam 18 carried by the shaft 19 journaled in bed 10 and bearing a worm gear 20. Worm gear 20 is driven through a train of gearing including worm 21, worm and worm wheel 22, 23 and change gears 24, 25, the latter being mounted on shaft 26 rotated by suitable motor 27. It will thus be seen that the cam is operated at a relatively slow rate of speed and that the amount of its eccentricity and its shape controls the rate and extent of movement of the regulating wheel support for effecting successive widenings and narrowings of the work receiving throat.

To effect rapid production, it is desirable that the operator be relieved, as far as possible, of control of the machine and that the work pieces be automatically presented to and removed from the grinding throat in timed relation to the movements of the regulating wheel and without necessity of stopping the machine between grindings.

To accomplish this result there is mounted on the bed 10 adjacent the grinding throat a guide chute or hopper 28 to receive the work pieces, this hopper having a lower guide 29 for the lower-most work pieces extending substantially into contact with the proximate end of the work rest blade 16 so that in event of any variance in diameter between the central and terminal portions of the unfinished work piece the same will be properly guided into position on the work rest blade.

For effecting transfer of the work pieces from the chute or hopper into the grinding throat, there is further mounted on the bed 10 a bracket 30 providing a guideway 31 for the slide 32 having an upwardly projecting arm 33 carrying the pusher 34. It will be noted that the pusher 34 has been shown as of sectional form having a removable terminal portion 35 interchangeable for proper engagement with different types of work pieces, thus increasing the range of adaptability of the machine.

Slide 32 bears centrally thereof a stud 36 projecting through slot 37 in the bracket 31 and provided with a roller 38 engaged between the curvatures 39 of rock arm 40. This arm has a hub 41 exteriorly supported in bracket 42 by 55

suitable anti-friction bearings 43, facilitating free oscillation of the arm. Interiorly, it is keyed to sleeve 44, having clutch disc 45 driven from shaft 46 through discs 47. A spring 48 serves to hold the parts together for suitable frictional actuation while permitting of slippage between the drive member 46 and arm 40 when resistance to movement of arm 40 exceeds a prescribed amount.

Member 46 has positively secured thereto for movement therewith a supplemental rock arm 49 having an arcuate head 50 provided with a central groove 51 receiving quadrant 52, normally held inwardly in the slot by spring 53.

Quadrant 52 has the laterally projecting pin 54 riding on the surface of cam 55 carried by clutch plate 45, this cam having an arcuate portion concentric with spindle 46 and an elongated notch or recess 56. So long as the movements of plate 45 and drive member 46 are in phase, pin 54 remains in the recess, but should an obstruction prevent movement of arm 40, the positive drive to member 46 will cause a slippage of the clutch and a consequent relative movement of pin 54 with respect to cam 55. As it is intended that a certain amount of movement may take part at this point without affecting operation of the machine, the pin will for a time ride in the recess, after which, however, it will ride onto the upper face of the cam, moving the quadrant outward. This outward movement reacts on roller 57 of safety switch 58, opening the control circuit of motor 27 and stopping the operation of the machine. An auxiliary manual push button control 59 is provided by which the motor may again be started, it being necessary manually to maintain this contact until the parts are restored to proper phased relation, as before described, when the quadrant will drop back to the position indicated in Figure 1, allowing the manual switch 59 to cause an automatic continued operation of the machine to be effected.

It should be apparent that the foregoing structure must be operated by an oscillatory movement and is not, as shown, capable of complete rotational driving as is the cam 18. To effect this movement of arm 40 in cyclically timed relation to the opening and closing of the grinding throat as determined by cam 18, there is secured on the spindle 19 of cam 18 a cylindrical or barrel cam 60 engaging pin 61 on reciprocable rack bar 62 having a rack portion 63 meshing with the peripheral teeth or pinion 64 on shaft 65 which transmits motion to the member 46. It will thus be seen that for each rotation of cam 18 there is a corresponding back and forth oscillation of member 62 effected by cam 60 and, therefore, a corresponding oscillation of arm 40 and consequently of pusher 35 actuated thereby.

It is to be understood that the work pieces drop by gravity into a position ahead of pusher 35 and the cycle is such that when the cam causes a retraction of the regulating wheel, opening the grinding throat, an inward movement or movement toward the right, as viewed in Figure 1, is imparted to the member 35 when the lowermost work piece in the chute 28 will be pushed toward the grinding throat moving ahead of it the completed work piece. In order that the work pieces may each individually be properly positioned in the throat and yet permit of ejection on completion, use is made of the oscillatable end stop 66, resiliently actuated as by spring 67 into the position shown in Figure 1 for engagement with the far terminus of the work

piece being operated upon. As the grinding is completed, however, face cam 68 secured to and movable with cam 18 actuates control plunger 69 of control switch 70 for solenoid 71 which serves to draw member 66 downward out of the path of movement of the work piece. This then permits the work piece to be moved out of the grinding throat, riding over the top of member 66 to an extent that it will by gravity tilt into the trough portion 72 thereof and be discharged from the machine. During continued movement of cam 18, a lower portion thereof is brought into alignment with control plunger 69, allowing the switch to move into position, opening the solenoid circuit when spring 67 will restore the end stop member to limit the movement of the following work piece.

To accommodate any variation in length of work pieces and insure same in all events being properly pressed into engagement with the end stop, bracket 42 is provided with the adjustable stop screws 73 and 74. On the inward or feeding stroke arm 40 is limited in its maximum movement by engagement with screw 73, while the drive effected through rack 62 is preferably a greater potential amount so that a certain counterclockwise slippage takes place in the driving clutch.

Correspondingly, this slippage will take place before arm 40 strikes screw 73 in the event that it is limited by the response of the work piece against the fixed end stop. Conversely, on movement of arm 40 in a reverse direction it will contact with screw 74 before maximum counterclockwise oscillation of member 46 has been effected, being, therefore, slipped back into its original phased relationship with the member 46 for re-engagement with a proper presentation of a subsequent work piece in the chute or trough 28. As has been pointed out, the length of notch 56 is such as to permit this slippage without effecting control switch 57.

In the event that for any reason it is desired to utilize the machine for grinding but a single work piece at a time, either for manual feeding of the work pieces, or for set-up purposes or where it is desired individually to check each work piece before grinding of a subsequent work piece, the cam shaft 19 may be utilized to perform a double function. In this event a supplemental face cam 75 is terminally secured thereto for cooperation with plunger 76 of switch 77, serving to move the switch to open the circuit of motor 27—preferably when the regulating wheel carriage is in a maximum retracted position. In this event, an additional manually controlled switch 78 is provided for temporarily closing the motor circuit to restart the cycle of operation of the machine. As will be seen by reference to the electrical circuit diagram, a selector switch 79 is further provided by which the switch 77 may be rendered either effective or ineffective, as respects control of the motor circuit.

From the foregoing description, taken in connection with the drawings, the operation of the present machine should be readily understood, and it will be understood that there has been provided a machine which may be either manually controllable, semi-automatic or completely automatic in operation, and which will serve satisfactorily to eject completed work pieces from the machine, introduce new work pieces, limiting definitely their positioning within the throat, and in which a positively opera-

ble drive in fixed timed relation with the movement of the regulating wheel for opening and closing the throat imparts a normally positive or potentially impositive movement to the control 5 arm for the work ejecting and injecting device, such that under proper operating conditions, the machine will be completely automatic in performance of the grinding, while in the event of improper work conditions or failure to release of 10 a part, such as the end stop, the machine will be automatically stopped and thus damage to the work or breakage of parts prevented. It will further be noted that there has been provided 15 a mechanism having an inherent slippage capacity, such as positively to insure accurate positioning of work pieces of variable lengths within the machine, which mechanism will be automatically self-restoring during each cycle of operation to normal prescribed position for operation 20 upon properly formed or standard length work blanks.

I claim:

1. The combination with a centerless grinding machine including opposed grinding and regulating 25 wheels forming a work supporting throat therebetween, and means for cyclically varying the width of said throat, of means for introducing work pieces within the throat of said grinder in timed relation to the variance in said throat, 30 said means including an oscillatable work shifting device, power actuating means for moving the device in timed relation to the throat varying movement of the centerless grinder, an impositive connection between said power means 35 and the oscillatable member, permitting slippage of the latter with respect to its actuator in the presence of an obstruction, and means responsive to a predetermined slippage for stopping the operation of the machine.
2. In a centerless grinding machine including opposed grinding and regulating wheels and an interposed work rest, means mounting one of said wheels for movement in a direction toward and from the other, means for injecting work 45 into the throat between the wheels during separation thereof and a control mechanism for said parts, including a drive motor, a control shaft rotatable thereby, a first cam means carried by the shaft for varying the effective dimension of 50 the work receiving throat, a second cam means carried by the shaft, an impositive connection between said second cam means and the work injecting mechanism for actuation of the latter, a safety control switch for the motor, and means 55 actuatable by out of phase movement between the throat control cam and the work injector for actuating the safety switch to stop the drive motor.
3. The combination with a centerless grinder 60 having opposing grinding and regulating wheels providing a work receiving throat, and means for automatically varying the width of said throat, of means for effecting movement of a work piece 65 in the throat including a cam operable by and in synchronism with the throat adjusting mechanism, a rock shaft oscillated by said cam, a work injector, and a friction coupling between said parts for effecting movement thereof with 70 and with respect to each other, a first stop device for limiting the movement of the work injector in a feeding direction whereby slippage in one direction will occur between said member and its actuator, and an additional means for 75 limiting its movement in a reverse direction for

restoring same to initially phased relation with respect to its actuator.

4. The combination with a centerless grinder having opposing grinding and regulating wheels providing a work receiving throat, and means for automatically varying the width of said throat, of means for effecting movement of a work piece in the throat including a cam operable by and in synchronism with the throat adjusting mechanism, a rock shaft oscillated by said cam, a work injector, and a friction coupling between said parts for effecting movement thereof with and with respect to each other, a first stop device for limiting the movement of the work injector in a feeding direction whereby slippage in one direction will occur between said member and its actuator, an additional means for limiting its movement in a reverse direction for restoring same to initially phased relation with respect to its actuator, a safety device for discontinuing actuation of the work injector drive, and means for actuation of the safety device when the relative movement of the parts exceeds a prescribed amount.

5. The combination with a centerless grinder 25 having opposing grinding and regulating wheels providing a work receiving throat and means for automatically varying the width of said throat, of a prime mover, means for effecting movement of a work piece in the throat, a friction safety 30 device, and means operable upon slippage of the safety device beyond prescribed limits for stopping the prime mover.

6. The combination with a centerless grinder 35 having opposing grinding and regulating wheels providing a work receiving throat and means for automatically varying the width of said throat, of a prime mover, means for effecting movement of a work piece in the throat, a friction safety device, and means operable upon 40 slippage of the safety device beyond prescribed limits for stopping the prime mover, said means including an electrical circuit, a switch in the circuit opened by said means to interrupt the circuit and additional means exclusive of said switch for completing the circuit to re-establish operation of the prime mover.

7. The combination with a centerless grinder 50 having opposing grinding and regulating wheels providing a work receiving throat and means for automatically varying the width of said throat, of a prime mover, means for effecting movement of a work piece in the throat, a friction safety device, means operable upon slippage of the safety device beyond prescribed limits for 55 stopping the prime mover, said means including an electrical circuit, a switch in the circuit opened by said means to interrupt the circuit and additional means exclusive of said switch for completing the circuit to re-establish operation of the prime mover, and automatically operable means for effecting reverse slippage of the safety device to restore the first-mentioned switch to circuit completing position.

8. The combination with a centerless grinder 65 having opposed grinding and regulating wheels providing a work receiving throat, of work feeding and grinding controlling mechanism for said grinder including a prime mover, a cam shaft actuated thereby having a first cam portion for 70 effecting contraction and expansion of the grinding throat, means for introducing and ejecting a work piece as respects the grinding throat, an end stop member for limiting movement of the work axially in the throat, electrically operated 75

means for shifting said end stop into inoperative position, a control switch for said electrical operated means and an operating member actuatable by said cam shaft for determining the effective positioning of said switch.

9. The combination with a centerless grinder having opposed grinding and regulating wheels providing a work receiving throat, of work feeding and grinding controlling mechanism for said 10 grinder including a prime mover, a cam shaft actuated thereby having a first cam portion for effecting contraction and expansion of the grinding throat, means for introducing and ejecting a work piece as respects the grinding throat, an 15 end stop member for limiting movement of the work axially in the throat, electrically operated means for shifting said end stop into inoperative position, a control switch for said electrical operated means and an operating member actuatable by 20 said cam shaft for determining the effective positioning of said switch, said work feeding mechanism including a pusher device for effecting axial movement of successive work pieces in the direction of said end stop, means on said cam shaft 25 for effecting actuation of said pusher device in timed relation to the throat widening and end stop releasing mechanisms, and a safety device including a power actuatable electric switch for effecting discontinuance of actuation of the cam shaft when resistance to movement of the pusher 30 exceeds a predetermined amount.

10. The combination with a centerless grinder having opposed grinding and regulating wheels providing a work receiving throat, of work feeding and grinding controlling mechanism for said 35 grinder including a prime mover, a cam shaft actuated thereby having a first cam portion for effecting contraction and expansion of the grinding throat, means for introducing and ejecting a work piece as respects the grinding throat, an 40 end stop member for limiting movement of the work axially in the throat, electrically operated means for shifting said end stop into inoperative position, a control switch for said electrical operated means and an operating member actuatable by 45 said cam shaft for determining the effective positioning of said switch, said work feeding mechanism including a pusher device for effecting axial movement of successive work pieces in the direction of said end stop, means on said cam shaft 50 for effecting actuation of said pusher device in timed relation to the throat widening and end stop releasing mechanisms, a safety device including a power actuatable electric switch for effecting discontinuance of actuation of the cam shaft 55 when resistance to movement of the pusher exceeds a predetermined amount, and means exclusive of said switch for re-establishing power actuation of said shaft.

11. In a machine of the character described,

a work shifting mechanism including a prime mover, a rock shaft actuatable thereby, a plunger, means for transmitting movement from the rock shaft to the plunger including a slip clutch, the amplitude of oscillation of the rock shaft exceeding the angular amplitude of potential movement of the plunger, whereby slippage will take place at each power oscillation of the rock shaft, means for re-establishing initial phased relationship of said parts during each complete oscillatory stroke, and means actuatable by excessive relative slippage of the parts as when an unwarranted obstruction unduly limits movement of the plunger for stopping the oscillation of the shaft.

12. In a machine of the character described, a work shifting mechanism including a prime mover, a rock shaft actuatable thereby, a plunger, means for transmitting movement from the rock shaft to the plunger including a slip clutch, the amplitude of oscillation of the rock shaft exceeding the angular amplitude of potential movement of the plunger, whereby slippage will take place at each power oscillation of the rock shaft, means for re-establishing initial phased relationship of said parts during each complete oscillatory stroke, and means actuatable by excessive relative slippage of the parts as when an unwarranted obstruction unduly limits movement of the plunger for stopping the oscillation of the shaft, said means including a segmental member movable 30 with the rock shaft, a switch member mechanically interengaged with the segment, and means for radially displacing the segment when the slippage between the parts exceeds a prescribed amount, whereby said radial displacement actuates the switch arm to stop the movement of the rock shaft.

13. A machine of the character described including means providing a variable width grinding throat, means for terminally limiting axial movement of a work piece in the throat, and a control mechanism for cyclically determining the operation of the machine, including a prime mover, a timer shaft driven by the prime mover, means actuated by the timer shaft for effecting intermittent variations in the width of the grinding throat, a shiftable terminal end stop member for limiting movement of the work in the grinding throat, control means including a solenoid for determining the effective position of the end stop member, means on the timer shaft for determining the energization of the solenoid in timed relation to variance of the grinding throat, a cyclic determinator selectively conditionable to effect uni-cycle or continuous operation of the machine, means on the timer shaft for controlling the uni-cycle mechanism, and means independent of the timer shaft control for initiating a succeeding cycle of operation.

FREDERICK S. HAAS.
